UNITED STATES PATENT OFFICE

Patent No. 2,374,750

DENTAL MATRIX RETAINER
Chester S. Ivory, Bala-Cynwyd, Pa., assignor to
The Estate of J. W. Ivory, Philadelphia, Pa.

Application December 6, 1944, Serial No. 566,847

2 Claims. (Cl. 32—63)

My invention relates to a dental matrix retainer of the type disclosed in my prior Patent No. 1,990,381.

One object of the invention is to produce an improved retainer of the type set forth.

A further object of the invention is to produce a more rigidly constructed retainer and one that is more easily manipulated.

A still further object is to produce an improved retainer whereby the matrix may be easily detached as soon as the need for it ceases, without the necessity of returning the parts to their ineffective position, as will be more fully later explained, thus reducing the work that has to be done in the patient's mouth and the time during which the mouth of the patient must be kept wide open.

These and other objects are effected by my invention as will be apparent from the following description and claims taken in connection with the accompanying drawing forming a part of this application, in which:

Fig. 1 is a side elevation of a matrix retainer embodying my invention before it is used;

Fig. 2 is a top plan view showing the retainer as it appears when in use in the mouth of a patient;

Fig. 3 is a bottom plan view of Fig. 1;

Fig. 4 is an enlarged fragmentary elevation of the left-hand end of the retainer shown in Fig. 1;

Fig. 5 is an enlarged fragmentary vertical sectional view of the left-hand end of the retainer as shown in Fig. 2, the teeth being omitted;

Fig. 6 is a section taken on line 6—6 in Fig. 1; and

Fig. 7 is an enlarged perspective view of a slide or carriage forming part of the construction.

Referring to the drawing, the retainer illustrated includes a flat, elongated body portion 10 having a slot 12 in the left-hand portion thereof. The slot 12 extends to within a short distance of the left-hand end of the body, as viewed in the drawing. At its left-hand end, the body portion terminates in an extension 14 having a slot 16 therein disposed at a right angle to the slot 12. The length of the slot 12 determines the range of adjustment of the device, as will later be more fully explained. To the underside of the extension 16, as viewed in Fig. 2, is secured a boxlike structure 18 having side walls 20, a bottom wall 22 and a top wall 24. The bottom wall 22 is provided with spaced narrow slots 26, and the top wall 24 is provided with a relatively wide slot 28 which coincides with the slot 16 in the extension

14. The boxlike structure 18 is secured rigidly in position by a screw or the like 30 engaging an extension of the top wall 24 and the extension 14 of the body 10, as clearly shown in Fig. 5.

On the top side of the body 10, as viewed in Fig. 2, is slidably mounted a carriage 32 which is shown detached in Fig. 7. From Fig. 7 it will be seen that the carriage includes side walls 34, 36 and 38 which form a U-shaped structure, the on the upper surface of the body as viewed in bottom edge of which, as viewed in Fig. 7, rides on the upper surface of the body as viewed in Fig. 2. The side wall 38 is doubled on itself to produce sufficient rigidity and is provided with a pendant tongue 40 adapted to engage the slot 12 so as to permit longitudinal movement of the carriage with reference to the body 10. It will be noted that the bottom edges of the walls 34 and 36 are cut away so as to produce a wedge-shaped space 42 between the left-hand portion of the carriage and the body 10, as best shown in Figs. 2 and 5.

The side wall 38 is provided with a tapped opening 44 for threadedly engaging the threaded end portion 46 of an actuating shaft or rod 48. The rod 48 passes loosely through an opening 50 in the angularly deflected end 52 of the body 10 and is provided at its other end with a manipulating knob or knurled handle 54. The wall 52 terminates in a forked portion 56 which extends parallel to the wall 52 and engages a grooved nut 58. The nut 58 threadedly engages a threaded portion 60 of the rod 48 and is provided with a knurled operating wheel 62. It will be seen that when the knob 54 is turned in one direction, the point 64 of the rod is moved towards and against the wall 34 of the carriage so that the gathered ends 66 and 68 of a matrix retainer 70 may be clamped tightly between the end of the rod and the wall 34 of the carriage, as shown in Fig. 2. To release the ends of the matrix, the knob 54 is turned in the opposite direction. Likewise, if the nut 58 is turned in one direction, the rod 48 and the carriage 32 carried thereby are moved towards the left-hand end of the device, and vice versa.

Operation

When it is desired to use the device, the carriage 32 is moved to its extreme left-hand position, until the tongue 40 reaches the end of the slot 12 and the slot 28 registers with the slot 16. The ends 66 and 68 of the matrix are then threaded through the spaced slots 26 in the bottom wall 22 of the boxlike structure 18, and through the

slots 28 and 16 until they extend up at least to the level of the rod 48, as shown in Fig. 2. The knob 54 is then turned until the rod 48 tightly clamps the ends of the matrix against the wall 34 of the carriage 32. As will be seen from Fig. 5, the body of the matrix, which is made of thin, flexible sheet metal having the desired width and tensile strength, now forms a loop considerably larger than a tooth having a cavity C to be treated. After the cavity has been prepared, the loop of the matrix is slipped over the tooth, and the nut 58 is turned to move the carriage 32 away from the tooth, or to the right as viewed in the drawing. The movement of the carriage to the right draws the loop 10 of the matrix tightly around the tooth so that a portion of the matrix forms a wall for the cavity C to confine the filling alloy packed into the cavity. In this position, the end portions of the matrix band are disposed in the space 42 between the bottom of the carriage and the body 10. When the cavity has been filled, it is merely necessary to turn the knob 54 to release the grip of the rod 48 on the ends of the matrix band, and since the end portions of the matrix are in the space 42, they are not tightly wedged between the bottom of the carriage and the body 10 and the retainer can be disengaged from the matrix by merely pulling the retainer out of the mouth. This leaves the matrix band in the mouth and it can be pulled out with a pair of forceps. By this construction, turning the nut 58 until the carriage 32 is returned to a position registering with the tooth, before the matrix band can be pulled vertically (downwardly or upwardly) from the tooth, is eliminated. This considerably shortens the time during which the mouth has to be kept open and permits removal of the matrix band at convenience. After the retainer is removed from the mouth, the carriage is returned to the position shown in Fig. 2, so as to be ready for further use.

What I claim is:

1. A dental matrix retainer comprising an elongated body portion having an elongated slot near one end thereof, a U-shaped carriage member including opposed side walls and an intermediate wall disposed on one side of said body member with said side walls extending transversely of said body member, a tongue depending from the side wall of the carriage remote from said end of said body member for slidably securing said carriage member to said body member, there being a threaded opening in said last-mentioned side wall, a shaft having a threaded portion engaging said opening, whereby when said shaft is rotated, in one direction, the end of said shaft is moved towards the other side wall of said carriage member, to clamp the ends of a matrix band against said other side wall, and whereby when said shaft is rotated in the opposite direction, the end of said shaft is moved away from said side wall to release the ends of said band, the underside of the portion of said carriage member facing said end of said body member being spaced from the adjacent surface of said body member, and means engaging said shaft for moving said carriage member longitudinally of said body member.

2. The structure recited in claim 1 together with a boxlike structure secured to the opposite side wall of said body member near said end thereof, said boxlike member having a slot in the wall thereof contiguous with said body member, and having spaced slots in the opposite wall thereof, there being a second slot in said body member near said end thereof registering with said slots in the walls of said boxlike structure, said second slot and the slots in the walls of said boxlike structure extending transversely of said body member and of said elongated slot.

CHESTER S. IVORY.
